SUCTION HEAD

Alexander Lissiansky, New York, N. Y., assignor
to International Mutoscope Corporation, Long
Island City, N. Y., a corporation of New York

Application January 1, 1943, Serial No. 471,051

7 Claims. (Cl. 274—10)

This invention relates to means for transferring sound record disks from a supply magazine to a phonograph turn-table and for removing the record disks from the turn-table. More particularly, the present invention is concerned with the suction head of the record-disk transferring means forming a part of my application for Machines for recording and dispensing phonograph records, Serial Number 372,532, filed December 31, 1940, and the present application is a continuation-in-part of my said prior application.

In accordance with the present invention and pursuant to one of the objects thereof, the suction head comprises means for preventing the communication of the interior of suction head with the central opening of the record disk and to provide an airtight joint between the suction head and the record-disk along a peripheral line spaced radially outwardly from the central hole of the record-disk and radially outwardly beyond the area of the upper disk surface to which suction is applied.

Another object of the invention is to provide a suction head provided with means for forming a suction chamber at the top of the record disk between the latter and the suction head.

Another object of the invention is generally to provide a suction head of improved construction and operation for moving record-disks to or from a support therefor.

The above and other objects, features and advantages of the invention will be fully understood from the following description, reference being had to the accompanying illustrative drawings.

In the drawings:

Fig. 1 is a sectional view on the line 1—1 of Fig. 2, the suction head being shown in full lines in position over the turn-table and in dotted lines in position over the record-disk supply magazine, parts being omitted for the sake of clearness of illustration;

Fig. 2 is a top plan view of the record-disk transferring means, including the suction head, in association with the record disk supply magazine and the phonograph turn-table;

Fig. 3 is a sectional view of the suction head, on a larger scale, on the line 3—3 of Fig. 1;

Fig. 4 is a vertical sectional view, on a larger scale, on the line 4—4 of Fig. 1, showing the suction head in engagement with the record disk;

Fig. 5 is a bottom plan view of the suction head.

Referring now to the drawings in detail, the suction head 10 forming a part of the record disk transferring means is mounted on the suc-

tion-head carrier 12 and is movable by the latter to and from the positions illustrated in full lines and in dotted lines in Fig. 1 for moving the record disks R, one at a time, from the supply magazine M to the phonograph turn-table T and from the latter to an intermediate position over a delivery chute C, the lower end of which communicates with a delivery opening in the front of the cabinet as illustrated in my abovementioned prior application.

As will be presently described, the suction-head carrier 12 is mounted for oscillation about a vertical axis whereby to position the suction head above the record disks in the supply magazine and to move the topmost record to a position on the turn-table and thereafter to move the record from the turn-table to a position over the discharge chute C. Also, as will be presently described, the suction head is mounted for vertical movement in relation to the suction-head carrier 12 for engaging the topmost record in the supply magazine and for lifting said record from the records therebelow in the magazine, for lowering the transferred record to its position on the turn-table, and for raising the record from the turn-table preliminary to the removal of the record therefrom to the discharge chute. The means for oscillating the suction-head carrier and for raising and lowering the suction head on the carrier are preferably the same as disclosed in my prior application and will, therefore, not be described herein except to the extent necessary to the explanation of the operation of the suction head as defined by the claims in this application.

The suction-head carrier 12 is a hollow tubular member having a horizontal part 14 and vertical parts 16 and 18 at the opposite ends thereof, respectively. Said suction-head carrier 12 is fixed to the upper end of a hollow vertical shaft 20 which passes through vertical end part 16 of carrier 12. An upper end portion 22 of shaft 20 is enlarged to provide a shoulder 24 by which shaft 20 is supported in vertical position on a stationary frame part 26 and for providing a shoulder 28 which is engaged by the confronting surface of the internal boss 30 formed in end portion 16 of carrier 12. The upper reduced end portion 32 of shaft 20 above shoulder 28 projects upwardly through said boss 30 and is engaged by a clamping nut 34 threaded thereon for fixing carrier 12 to the shaft 20 for turning movement therewith. Nut 34 clamps the shoulder 28 against the inner edge of boss 30 and is itself clamped in position against the outer surface of carrier

member 12 with an interposed lock washer 36. Shaft 20 is journaled for turning movement in a bearing bushing 38 provided in frame part 26 and in a bearing bushing 40 mounted in a stationary frame part 42. The lower end of shaft 20 is provided with a gear 44 which is engaged by a companion gear member (not shown) actuated as described in my above mentioned application for oscillating shaft 20 about its vertical axis. The lower end of part 16 of carrier 12 communicates with a chamber 46 in frame part 26, said chamber having an opening 48 which communicates with a source of suction as described in my prior application.

The suction head 10 comprises a cylindrical tubular member 50 having an upper portion 52 which has a slideable and rotatable fluid-tight fit with the inner cylindrical surface 54 of the lower end portion 56 of the end part 18 of carrier 12. Said tubular part 50 of the suction head communicates with the interior of carrier member 12 through a plurality of openings 58, the interior of member 12 being in communication with the source of suction through chamber 46. Above said openings 58, member 50 of the suction head is provided with an integral cylindrical portion 60 which has a slideable and rotatable fluid-tight fit in an opening 62 in the top of end part 18. The vertical movement of suction head 10 is provided for by the mechanism which includes the lever 64 pivotally mounted between its ends on a pin 66 carried by brackets 68 at the top of carrier 12. The upper enlarged end portion 70 of the cylindrical stem 71 of suction head is engaged by the forked end 72 of one arm of lever 64. The other arm of the lever is engaged at its end by a sleeve 74 in which the end of a cable 76, such as a wire or cord, is fixed. Said cable 76 extends longitudinally through hollow shaft 20 to a point below the lower end of said shaft where said cord is engaged by the mechanism described in my prior application for moving said cable downwardly and for permitting said cable to move upwardly in timed relation to the actuation of shaft 20. It will be understood that when cable 76 is moved downwardly, lever 64 is operated for raising the suction head and that when said cable is allowed to move upwardly the suction head can move downwardly under its weight. A spring 78 secured to the top of carrier member 12 and bearing on lever 64 assists the downward movement of the suction head and resiliently opposes the upward movement thereof. Suction head 10 is provided with a flange 80 which is engageable with the lower end portion 56 of carrier member 12 for limiting the upward movement of the suction head.

Suction head 10 is provided with a pick-up plate 82 which is engageable with and disengageable from the record disk for moving the latter from the magazine and to the turn-table and from the turn-table to the discharge chute. The pick-up plate 82 comprises a disk 84 provided with a central upwardly projecting cylindrical portion 86 which is screw-threaded externally thereof and is threaded into the companion lower end of tubular member 50 of the suction head whereby the pick-up plate 82 is removably secured to said member 50 in fluid-tight relation therewith. The lower surface of disk 84 is provided with a circular recess 88 in which is adhesively or otherwise secured the circular gasket or packing ring 90. Said packing ring 90 is preferably resilient and may be formed of cork, soft rubber or any other suitable packing material.

Pick-up plate 82 is provided with means for sealing the central opening O of the record disk from communication with the interior of the suction head. Said sealing means comprises a soft rubber or other resilient gasket or packing ring 92, the lower end of which engages the upper surface of the record disk near and completely around the central opening O of said disk. As illustrated in Fig. 4, packing rings 90 and 92 when engaged with the upper surface of the record disk R define a suction chamber 94 above the record-disk between the outer peripheral edge of packing 92 of the inner peripheral edge of packing 90 completely therearound, and said packing rings prevent loss of suction which might otherwise occur either through central opening O of the record-disk or through any space which might be present between the lower surface of plate 84 and the upper surface of the record-disk, if said plate were in direct contact with said record in the absence of the packing ring 90.

Gasket 92 is mounted for movement in pick-up plate 82 axially thereof. For this purpose, said packing 92 is carried by a member 96 which is provided with a central vertical extending recess 98 for receiving the centering pin 99 of the turn-table or the upper end portion of the centering rod 100 of the supply magazine when the suction-head is positioned over the turn-table and supply magazine, respectively, in engagement with the record disk. Said member 96 is guided for movement in a cylindrical opening 102 formed in the hub member 104. Said hub member 104 is integral with part 86, being spaced radially inwardly thereof and connected thereto by the spider portions 106 providing openings 108 in the pick-up plate to provide communication between the exterior of the pick-up plate and the interior of the suction head. The packing carrying member 96 is provided with an upper stem 110 which projects through an opening 112 in hub part 104. A pin 114 passing through the outer end of stem 110 limits the downward movement of member 96. A spring 116 bearing at one end thereof against member 96 and at its other end against the top of hub part 104, presses member 96 and the packing 92 carried thereby downwardly for resilient engagement with the record disk. The parts of pick-up plate 82 are so dimensioned that packing member 92 is projected by spring 116 to a point below the outer surface of packing ring 90 so that said packing ring member 96 is in a position to engage the upper surface of the record-disk in the magazine before said surface is engaged by gasket 90 while the suction-head is descending for engaging the record-disk. During the descent of the suction-head from a position above the record-disk to a position in which the pick-up plate engages said disk, the lower edge of packing ring 92 is engaged by the record-disk and moves upwardly with member 96 in hub part 104 against the resilient pressure of spring 116 and packing ring 90 engages the upper surface of said record-disk. The upward movement of member 96 in hub part 104 is limited by a shoulder 118 of hub member 104.

In order to fixedly secure packing ring 92 to member 96 in such manner as to prevent movement thereof longitudinally of said member, the outer surface portion 120 of member 96 is tapered upwardly. It will be observed that as shown in Fig. 4, the packing member 92 extends downwardly below the lower end of member 96 to provide said packing member with a lower resilient end portion which is not interfered with by the

carrying member 96. The flange 122 prevents movement of gasket 92 upwardly on member 96. The outer surface of gasket 92 is preferably cylindrical in parallel relation to the adjacent inner cylindrical surface of hub member 104.

It will be understood that after the record-disk is moved from the supply magazine and placed on the turn-table T, the suction-head remains in engagement with the upper surface of the record and rotates therewith during the rotation of the record by the turn-table, the weight of said suction-head pressing the lower surface of said record against the friction plate 124 of the turn-table for increasing the traction friction between said plate and the record. After the sound-record is recorded and/or reproduced, the suction head is raised to lift the record from the turn-table and then the carrier is turned to position the record over the discharge chute C. When the record is positioned over the discharge chute C, the suction to head 10 is interrupted, preferably as described in my above mentioned prior application, and the record drops from the head 10 onto the chute C. As here shown, chute C is provided with an upturned edge portion 126 against which the record strikes and which causes the record to tilt downwardly toward the magazine M, so that there is sufficient room for the record in the space between the magazine and the turn-table as the record begins its descent on the chute to the discharge opening of the cabinet shown in my prior application.

While I have shown and described the preferred embodiment of my invention, it will be understood that the latter may be embodied otherwise than as herein specifically shown or described, and that in the illustrated embodiment certain changes in the details of construction and in the arrangement of parts may be made without departing from the underlying idea and scope of my invention. Accordingly, I do not wish to be limited to the construction herein specifically shown or described except to the extent which may be required by the scope of the appended claims.

Having thus described my invention, what I claim and desire to secure by Letters Patent is:

1. In a suction head comprising a tube adapted to be connected to a source of suction, and a pick-up plate carried by said tube, said pick-up plate having an opening therethrough for the application of the suction in said tube to the exterior of said plate, a gasket-carrying member mounted for movement axially of said plate, a gasket carried by said member, resilient means urging said gasket-carrying member and the gasket carried thereby to a projected position, and a gasket carried by said plate and extending around said first mentioned gasket in laterally spaced relation thereto, the outer end of said opening being located in the space between said gaskets.

2. In a device of the character described comprising a suction-head carrier mounted for oscillation about a vertical axis, and a suction head mounted on said carrier for movement therewith and also for movement thereon parallel to said axis, said suction head comprising a member having a passage therein adapted to be connected to a source of suction, a plate carried by said member and having an opening therethrough communicating with said passage, said plate having a pick-up side through which said opening extends and in which the outer end of said opening is located, and a plurality of spaced gaskets disposed in radially spaced relation on said pick-up

side of said plate co-axially with said plate and surrounding the outer end of said opening, the outer end of said opening being located in the space between said gaskets.

- 5 3. A device of the character described comprising a suction-head carrier mounted for oscillation about a vertical axis, a suction head mounted on said carrier for movement therewith and also for movement thereon parallel to said axis, said suction head comprising a member having a passage therein adapted to be connected to a source of suction, a plate carried by said member, said plate having an opening communicating with said passage and extending from the inner side of said plate to the opposite outer side thereof, said plate having an axially extending guideway therein opening into said outer side of the plate, a gasket-carrying member slidably mounted in said guideway axially of said plate, a tubular gasket carried by said member and projecting through said opening of said guideway to the outer side of said plate, said gasket extending around the plate axis, resilient means acting on said gasket-carrying member to resiliently oppose the axial movement of said gasket toward the inner side of said plate, and a gasket on the outer face of said plate spaced radially outwardly of said tubular gasket, the outer end of said opening in the plate being located between said two gaskets.
- 20 4. A device of the character described for transferring a record-disk to and from a phonographic turn-table which has a centering pin which projects into the center hole of the record-disk when the latter is on the turn-table, said device comprising a suction head adapted to be mounted for vertical movement above said turn-table toward and away from said turn-table, said suction head comprising a member having a passage therein adapted to be connected to a source of suction, a plate at the lower end of said member, said plate having a pick-up side and having an opening therethrough, said opening having an inner end in communication with said passage, the outer end of said opening being located at the pick-up side of said plate and spaced laterally of the plate axis, a gasket-carrying member mounted on said plate for movement axially thereof and positioned radially inwardly of said outer end of said opening, the lower end of said gasket-carrying member having a recess in which said centering pin of the turn-table projects when the suction head is lowered to place the record-disk on the turn-table, a gasket carried by said carrying member and having a portion disposed below said carrying member for fluid-sealing engagement with the upper surface of the record disk around said central opening thereof whereby to prevent the transmission of suction from said passage to said record-disk opening, and a gasket carried by said plate in position radially outwardly of said first mentioned gasket in spaced concentric relation thereto, said end of the opening being located between said two gaskets.
- 25 5. A device of the character described for transferring a record-disk to and from a phonographic turn-table which has a centering pin which projects into the center hole of the record-disk when the latter is on the turn-table, said device comprising a suction head adapted to be mounted for vertical movement above said turn-table toward and away from said turn-table, said suction head comprising a member having a passage therein adapted to be connected to a source of suction, a plate at the lower end of said mem-

ber, said plate having a pick-up side and having an opening therethrough, said opening having an inner end in communication with said passage, the outer end of said opening being located at the pick-up side of said plate and spaced laterally of the plate axis, a gasket-carrying member mounted on said plate for movement axially thereof and positioned radially inwardly of said outer end of said opening, the lower end of said gasket-carrying member having a recess in which said centering pin of the turn-table projects when the suction head is lowered to place the record-disk on the turn-table, a gasket carried by said carrying member and having a portion disposed below said carrying member for fluid-sealing engagement with the upper surface of the record disk around said central opening thereof whereby to prevent the transmission of suction from said passage to said record-disk opening, and a gasket carried by said plate in position radially outwardly of said first mentioned gasket in spaced concentric relation thereto, said end of the opening being located between said two gaskets, the lower edge of said first mentioned gasket being below the lower edge of said other gasket when the suction-head plate is spaced upwardly from the record-disk on said support whereby said first mentioned gasket engages the upper surface of said record-disk before it is engaged by said other gasket when said suction-head plate is lowered to said record-disk.

6. A device of the character described for transferring a record-disk from a horizontal support having a vertical centering rod which projects upwardly through the central opening of said record-disk, said device comprising a suction head adapted to be mounted for vertical movement above said support and toward and away therefrom, said suction head comprising a member having a passage therein adapted to be connected to a source of suction, a plate at the lower end of said member, said plate having a pick-up side and having an opening therethrough, said opening having an inner end in communication with said passage, the outer end of said opening being located at the pick-up side of said plate and spaced laterally of the plate axis, a gasket-carrying member mounted on said plate for movement axially thereof and positioned radially inwardly of said outer end of said opening, the lower end of said gasket-carrying member having a recess in which said centering rod projects when the suction head is lowered to engage the record-disk on said support, a gasket carried by said carrying member and having a portion disposed below said carrying member for fluid-sealing en-

gagement with the upper surface of the record disk around said central opening thereof whereby to prevent the transmission of suction from said passage to said record-disk opening, and a gasket carried by said plate in position radially outwardly of said first mentioned gasket in spaced concentric relation thereto, said end of the opening being located between said two gaskets, the lower edge of said first mentioned gasket being below the lower edge of said other gasket when the suction-head plate is spaced upwardly from the record-disk on said support whereby said first mentioned gasket engages the upper surface of said record-disk before it is engaged by said other gasket when said suction-head plate is lowered to said record-disk.

7. A device of the character described for moving from a horizontal support a record-disk which has a central opening, said device comprising a suction-head adapted to be mounted above said support for vertical movement toward and away from the record thereon to engage the upper surface of said disk and raise the same from said support, said head having an opening for the application of suction to said surface of the record disk, means carried by said head engageable with said record-disk for sealing said opening therein from communication with said suction-head opening, and fluid-sealing means carried by said head and engageable with said surface of the record-disk along a peripherally extending line spaced radially outwardly of said central opening of the record-disk and radially outward beyond the area of application of suction to said surface of the disk through said suction-head opening, the lower edge of said first mentioned fluid-sealing means being below the lower edge of said other fluid-sealing means when the suction-head is spaced upwardly from the record-disk on said support whereby said first mentioned fluid-sealing means engages the upper surface of said record-disk before it is engaged by said other fluid-sealing means when said suction-head is lowered to said record-disk, said first-mentioned sealing means being mounted for movement axially in relation to said suction head, and resilient means for moving and pressing said first mentioned sealing means resiliently against said record-disk.

50

ALEXANDER LISSIANSKY.
